UNITED STATES PATENT OFFICE

172,982

TRAILER SHELTER HOUSE

George D. Parr, Huntington Park, Calif.

Application October 19, 1953, Serial No. 27,229

Term of patent 7 years

(Cl. D13--1)

To all whom it may concern:

Be it known that I, George D. Parr, a citizen of the United States, residing in Huntington Park, California, have invented a new, original, and ornamental Design for a Trailer Shelter House, of which the following is a specification, reference being had to the accompanying drawing, forming part thereof.

Fig. 1 is a plan view of a trailer shelter house, showing my new design.

Fig. 2 is a front elevational view thereof.

The sides of the building not shown are similar to those shown in Fig. 2.

I claim:

The ornamental design for a trailer shelter house, substantially as shown and described.
